S. W. MILLIGAN

LIQUID HOLDING CAN

Filed Jan. 22, 1924

Patented Nov. 25, 1924.

UNITED STATES PATENT OFFICE.

STEPHEN W. MILLIGAN, OF NEWARK, NEW JERSEY, ASSIGNOR TO THE MANUFACTURERS CAN CO., OF HARRISON, NEW JERSEY.

LIQUID-HOLDING CAN.

Application filed January 22, 1924. Serial No. 687,841.

To all whom it may concern:

Be it known that I, STEPHEN W. MILLIGAN, a citizen of the United States, residing at Newark, in the county of Essex and State of New Jersey, have invented certain new and useful Improvements in Liquid-Holding Cans; and I do declare the following to be a full, clear, and exact description of the invention, such as will enable others skilled in the art to which it appertains to make and use the same.

My invention relates to improvements in shipping and pouring cans for numerous kinds of liquids, such as varnishes, syrups, lubricating oils, etc. Cans of this character are often provided with pressed metal caps carrying swivel spouts for pouring purposes, and it is customary to place a sealing wafer between the cap and the neck of the can and to then tighten the cap with a pair of pliers, in order to provide a liquid-tight seal. This manner of tightening the caps is rather troublesome and causes a great deal of difficulty when the purchasers must open the cans. It is one object of my invention to provide finger-grips for tightening and loosening the screw-cap, without the necessity of using pliers or the like, these finger-grips being formed by outwardly bending portions of a continuous metal band which is soldered or otherwise secured around the depending threaded flange of the cap, whereby the band not only carries the finger-grips, but effectively reinforces the cap flange to prevent possible spreading thereof when the cap is tightened. The finger-grips are also of advantage in holding the cap against possible unscrewing, when adjusting the swivel spout from an operative to an inoperative position, or vice versa.

Cans of the type to which I have referred, are commonly provided with arched handles extending over their tops, and when a number of the cans are packed in a case, these handles will prevent the pouring spout from coming in contact with a side of the case or with other cans, unless the handle becomes bent during rough handling of the case. When such bending of the handle occurs, the spout is permitted to strike other cans, or a side of the case, as the case may be, and consequently, it also is damaged. It is a further object of my invention however, to provide a plug normally held between the handle and the can top to assist in preventing

bending of said handle, the plug being easily removable however for use to close the can, after initial opening thereof.

With the foregoing in view, the invention resides in the novel subject matter herein-after described and claimed, the description being supplemented by the accompanying drawing.

Figure 1 is a plan view of a can embodying my improvements.

Figure 2 is a vertical sectional view as indicated by line 2—2 of Fig. 1, showing the can sealed.

Figure 3 is a detail sectional view showing the can opened and the spout positioned for pouring.

Figure 4 is an additional vertical sectional view on the plane indicated by line 4—4 of Fig. 1, but showing the plug used to close the can after initial opening.

Figure 5 is a horizontal sectional view on line 5—5 of Fig. 4.

Figure 6 is a side elevation illustrating the manner in which a number of the cans may be stacked in a packing case.

In the drawing above briefly described, the numeral 1 designates a metal can of the type above referred to, said can being provided with a threaded neck 2 connected with its top 3, and having an arched handle 4 extending over said top. A threaded sheet metal cap 5 normally clamps a sealing wafer 6 upon the neck 2 and I have shown said cap provided with a swiveled pouring spout 7 which may be turned from an inner position, at which it overlies the can top, as in Fig. 1, to an extended operative position, as disclosed in Fig. 3.

Tightly surrounding the flange 8 of the cap 5 and secured to said cap by soldering throughout its circumference or otherwise, is a seamless metal band 9, spaced portions of this band being outwardly stamped as indicated at 10 to provide loop-like finger-pieces by means of which the cap may be easily applied and removed, without the use of pliers. Furthermore, when adjusting the swivel spout 7, the finger-pieces 10 are instrumental in holding the cap against possible turning with said spout.

The handle 4 is of such height as to protect the spout 7 when the latter is swung to an inner position and a number of the cans are packed in a case for shipment, and inward bending of this handle which would

result in injury to the spout, is resisted by a stamped metal plug 11 which is held between the handle 4 and the can top 3, this top being provided with a shallow depression 12 under said handle, into which the plug is snapped, to hold it normally in place. As shown in Fig. 4, the plug 11 is usable to close the opening 13 through the cap 5, after the can has been initially opened.

10 After filling the can, the cap 5 is screwed in place by means of the finger-grips 10 to tightly secure the sealing wafer 6 against the can neck 2, and when a purchaser receives the can, the finger-pieces 10 are employed 15 to unscrew the cap, permitting the wafer 6 to be removed and either thrown away or kept for future use. Then, the cap is rethreaded into place as shown in Fig. 4 and after properly adjusting the spout 7, it will be seen 20 that the contents of the can may be discharged with ease. After the pouring operation, the plug 11 may be removed from the handle 4 and pressed manually into the opening 13, to close the can for future use.

25 If desired, instead of using this plug, the wafer 6 may again be employed, but when it is necessary to discharge some of the contents of the can at frequent intervals, it is most desirable to use the plug 11. The 30 disk or wafer 6 preferably comprises an upper layer of tin, a lower layer of tin foil and an intermediate layer of yieldable packing material.

35 As excellent results have been obtained from the details disclosed, these details are preferably followed, but within the scope of

the invention as claimed, numerous minor changes may be made.

I claim:

1. The combination with a screw cap having a threaded flange; of a metal band secured around said flange to reinforce the same and bent outwardly into U-shape at intervals to provide finger-pieces for easily turning the cap. 40

2. The combination with a screw-cap having a threaded flange and a swiveled pouring spout; of a metal band secured around said flange to reinforce the same and bent outwardly into U-shape at intervals to provide finger-grips for turning the cap and for holding it against turning when adjusting the spout. 45

3. A liquid holding can having a shallow depression in its top, and an arched handle 50 extending over said depression; together with a closure removably held in said shallow depression by said handle and adapted to close the can after initial opening thereof. 55

4. A liquid holding can having a threaded outlet neck, a screw cap threaded on said neck and having a pouring opening, and a packing disk removably clamped between said cap and the outer edge of said neck, 60 said disk comprising an upper layer of tin, a lower layer of tin-foil to yieldably engage the neck of the can, and an intermediate layer of yieldable packing material. 65

In testimony whereof I have hereunto affixed my signature.

STEPHEN W. MILLIGAN.
